J. J. GORMAN,
VALVE GRINDER,
APPLICATION FILED APR. 2, 1917.

1,295,303.

Patented Feb. 25, 1919.

Inventor

JAMES J. GORMAN

By Watson E. Coleman

Attorney

UNITED STATES PATENT OFFICE.

JAMES J. GORMAN, OF DURANGO, COLORADO.

VALVE-GRINDER.

1,295,303.

Specification of Letters Patent. Patented Feb. 25, 1919.

Application filed April 2, 1917. Serial No. 159,253.

To all whom it may concern:

Be it known that I, JAMES J. GORMAN, a citizen of the United States, residing at Durango, in the county of La Plata and State 5 of Colorado, have invented certain new and useful Improvements in Valve-Grinders, of which the following is a specification, reference being had to the accompanying drawings.

- 10 This invention relates to certain improvements in valve grinders and has relation more particularly to a device of this general character especially designed and adapted for use in connection with water faucets; 15 and it is an object of the invention to provide a novel and improved device of this general character which may be applied with convenience and facility and wherein the grinding disk or member is automatically maintained in requisite engagement with the valve seat to be ground through the medium of an expansible member interposed between said disk or member and the cap of the faucet. 20 The invention consists in the details of construction and in the combination and arrangement of the several parts of my improved valve grinder whereby certain important advantages are attained and the device is rendered simpler, less expensive and otherwise more convenient and advantageous for use, all as will be hereinafter more fully set forth.

The novel features of the invention will 25 hereinafter be definitely claimed.

In order that my invention may be the better understood, I will now proceed to describe the same with reference to the accompanying drawings, wherein—

- 30 Figure 1 is a view partly in elevation and partly in section illustrating a grinding tool constructed in accordance with an embodiment of my invention and in applied position;

40 Fig. 2 is an outer face view of the grinding disk or member as herein embodied; and

Fig. 3 is an outer face view of the polishing disk or member as herein disclosed.

As disclosed in the accompanying drawings, F denotes a faucet provided with the internal valve seat S and with the remov-

able cap C, all of which are embodied in the structure of the faucet proper. To grind the valve seat S it will be understood that the conventional stem and valve is removed 55 together with the cap C.

The cap C is then slipped over the elongated shaft or stem 1 of my improved grinding tool. One end of the stem or shaft 1 is provided with the hand grasp 2 herein disclosed as of a wheel type whereby the requisite rotation may be imparted to the shaft, while the opposite end of the shaft or stem 1 is provided with the threaded extension 3 of a diameter less than the diameter of the stem or shaft 1, whereby an annular shoulder 4 is afforded.

After the cap C has been properly applied upon the stem or shaft 1 the cutting or grinding disk or member 5 is then threaded 70 upon the extension 3 until the same abuts the annular shoulder 4. The outer face of the disk or member 5 is provided with an annular beveled surface provided with the substantially radially disposed cutting 75 shoulders 6 whereby it will be perceived that when said member or disk 5 is in contact with the valve seat S and movement imparted to the shaft or stem 1 in one direction, the valve seat S will be planed or cut 80 to a smooth and even substantially concave surface.

Before the member or disk 5 is engaged with the extension 3 the expansible member 7 is slipped upon the stem or shaft 1, said 85 expansible member being herein disclosed as a conventional coil spring encircling the shaft or stem. The member 7 is of such a length as to be placed under compression or tension when the cap C is operatively engaged with the bonnet 8 of the faucet. When the member or disk 5 is in applied position the member 7 is in contact with the inner face or surface thereof, whereby said disk or member 5 is constantly urged toward 95 the valve seat S and maintained in requisite contact therewith.

After the seat S has been properly planed or cut it is preferred that the disk or member 5 be removed and the second disk or 100 member 9 substituted therefor. This member 9 is provided with a plane or smooth

beveled surface 10 which, when properly operated relative to the seat S, serves to smooth and polish the same. The member or disk 9 may be employed either with or without 5 a fine abrasive material.

After the valve seat S has been properly ground it will be at once self-evident that the stem or shaft 1 and its concomitant parts may be readily and conveniently removed 10 and the valve and valve stem of the faucet be readily replaced.

From the foregoing description, it is thought to be obvious that a valve grinder constructed in accordance with my invention 15 is of an extremely simple and comparatively inexpensive nature and is particularly well adapted for use by reason of the convenience and facility with which it may be assembled, and it will also be obvious that 20 my invention is susceptible of some change and modification without material departure from the principles and spirit thereof and for this reason I do not wish to be understood as limiting myself to the precise arrangement and formation of the several 25 parts herein shown in carrying out my in-

vention in practice, except as hereinafter claimed.

I claim:

Means for reseating the internal seat of a 30 faucet comprising a shaft freely insertible through the cap of the faucet and capable of direct endwise movement, a grinding disk detachably engaged with the end portion of the shaft within the faucet, the outer faces 35 of said disk being provided with an annular beveled surface engageable with the internal valve seat for grinding the same, and a spiral spring surrounding the shaft and contacting with the grinding disk, said spring 40 being of such a length as to contact with the under faces of the cap of the faucet for placing said spring under compression when the cap is engaged with the faucet, the outer 45 end of the shaft being provided with a hand grasp for rotating the same.

In testimony whereof I hereunto affix my signature in the presence of two witnesses.

JAMES J. GORMAN.

Witnesses:

FRANK H. RIVERS,
DANIEL J. CUMMINS.
